UNITED STATES PATENT OFFICE.

FRED E. NORTON, OF LYNN, MASSACHUSETTS, ASSIGNOR TO GENERAL ELECTRIC COMPANY, A CORPORATION OF NEW YORK.

ELASTIC-FLUID TURBINE.

1,094,393.

Specification of Letters Patent. Patented Apr. 21, 1914.

Application filed February 13, 1913. Serial No. 748,061.

To all whom it may concern:

Be it known that I, FRED E. NORTON, a citizen of the United States, residing at Lynn, in the county of Essex and State of Massachusetts, have invented certain new and useful Improvements in Elastic-Fluid Turbines, of which the following is a specification.

The present invention relates to elastic fluid turbines and has for its object to provide a turbine and governing mechanism therefor so organized and arranged that the turbine may operate as a high pressure machine, as a low pressure machine, as a mixed pressure machine or as an extraction machine, according to the conditions of service.

A further object of my invention is to provide a turbine and governing mechanism therefor so organized and arranged that the turbine operates at the same speed for a given load irrespective of the character of the steam supply or the amount of steam extracted therefrom, thereby enabling it to be operated in synchronism with other machines.

Briefly stated, my invention comprises a multi-stage turbine having a suitable inlet and an outlet, together with a conduit connected to an intermediate pressure stage through which steam may be extracted for heating, cooking, or other industrial purposes, or through which low-pressure steam may flow from any source, to said intermediate pressure stage, and subsequently do work in the turbine.

The admission of high-pressure steam to the turbine is controlled by a valve means that is responsive to a speed governor driven by the turbine, a second valve means, also governor-controlled, regulates the passage of steam through the turbine from an intermediate pressure stage to a low pressure stage, and also determines the pressure of the extracted steam and regulates the passage of the low-pressure steam from a separate source. The action of the governor on these valve means is, however, subject to two separate and distinct modifying means, one being active all the time, the other being active only when the turbine is operating as a mixed pressure machine. The first of these means is responsive to the pressure existing

in some region or portion of the machine, such for example as an intermediate stage thereof or in a conduit in direct communication therewith, such for example as the conduit for conveying steam therefrom or thereto as the case may be. Specifically considered a valve is located in the turbine and so arranged as to cut nozzles or fluid-discharging devices or passages into and out of service in a manner to maintain a constant stage pressure under varying load conditions. Such a valve has the advantage of improving the efficiency of the machine by maintaining the proper distribution of fluid pressure therein and maintaining the proper pressure of the steam supplied to the heating devices, etc. The valve is motor-operated and is controlled, as before stated, by the speed governor and also by a diaphragm or equivalent device that is sensitive to variations in pressure in said stage or in a conduit in communication therewith. The preferable arrangement is to directly expose the diaphragm or equivalent device to stage pressure thereby avoiding any drop in pressure which might otherwise take place and simplifying the apparatus. The second of said means is responsive to changes in the rate of flow of low pressure steam through said conduit from any suitable source, such for example as the exhaust conduit of a high pressure engine of any type. Specifically this means comprises a device such as a Venturi or Pitot tube or a combination of both located in the supply conduit and which is capable of establishing a pressure difference that bears a definite relation to changes in the rate of flow of fluid in said conduit. This pressure difference is communicated to opposite sides of a diaphragm or equivalent device that acts differentially on the high pressure inlet and also on the intermediate pressure or stage valves to close one and open the other as circumstances require. This action is entirely independent of the speed governor which normally moves the valves simultaneously and correspondingly.

The use of a flow responsive device possesses marked advantages over the pressure responsive devices now in use because it does not become operative until a flow has been established for an appreciable interval of

time and hence will not take into account a momentary impulse or supply of steam such for example as would be occasioned by the simple turning over of a rolling mill engine whose exhaust pipe delivers steam to the turbine. In other words with a pressure sensitive device and a variable steam supply the turbine is being continually shifted over from high to mixed pressure operation and back again, thereby giving rise to irregularities in speed which are highly objectionable for many purposes, notably where the turbines drive alternating current generators connected in multiple with other generators driven by separate prime movers. Furthermore the flow responsive device insures the same position of the speed governor for the same load irrespective of whether the supply of steam entering the turbine is high, low or mixed pressure. It is this feature which enables the turbo-generator to operate in synchronism with other generators driven by separate prime movers, such as water wheels for example. In this connection it should be borne in mind that the ordinary type of speed governor has a predetermined range of movement from no load to full load and that if such a governor is used on a mixed pressure machine without some modifying means one portion of said range must be devoted to low pressure operation and the remainder to high and mixed pressure operation in which latter case both high and low pressure steam is delivered to the turbine. As a result of this the turbine may be effectively governed when operating by itself but will take too little or too much of the total load when working with another machine unless the supplies of energy to all turbines change simultaneously and in like manner and amount. This in practice is seldom or never the case.

Viewed as an extraction turbine the governing mechanism is so constructed and arranged that a supply of steam at constant and predetermined pressure is available in the extraction stage and from which it flows to the heating, cooking or other devices, the balance of the steam passing through the turbine and performing work therein on its way to the outlet or condenser.

Particularly I desire to emphasize the fact that, due to my improved apparatus, the speed of the turbine can be maintained the same for any load regardless of whether it be operating as high pressure, low pressure, mixed pressure or as an extraction machine.

In the accompanying drawings which are illustrative of my invention, Figure 1 is a perspective view of a turbo-generator; Fig. 2 is a diagrammatic view of the turbine and governing mechanism; Fig. 3 is a detail view, chiefly in section, of the extraction stage valve and the motor for operating it;

Fig. 4 is a sectional view of a part of the fluid measuring device, and Fig. 5 is a plan view of the same.

Referring to Fig. 1, 5 indicates an electric generator of the alternating current type and 6 a multi-stage turbine of the Curtis type for driving it. The invention is not, however, limited to the type of generator or turbine shown, but is of general application. 7 indicates the inlet of the turbine through which high pressure steam flows under the control of one or more valves 8 that are actuated directly or indirectly by the speed governor 9, the latter being driven by the turbine shaft in any suitable or usual way. 10 indicates the outlet or exhaust conduit leading to a condenser, and 11 the conduit through which steam flows from the extraction stage to the heating devices or through which low pressure steam is admitted to the turbine. The admission of high pressure steam is controlled by the valve 8, that may be taken as typical of any suitable valve means. It is provided with a stem 12, and engaging a pin or collar thereon is a forked lever 13, the outer end of which is rigidly connected to the pivotally supported governor lever 14. The lever is connected by a rod 15 with a three-arm lever 16, the latter being supported by a counter weighted arm 17 that is mounted on the rock shaft 18. The rock shaft is supported in suitable bearings and motion is imparted thereto from the speed governor 9 by the rocker arm 19 that is connected to the movable abutment of the governor. As the speed varies due to load changes, more or less steam will be admitted in the usual manner, assuming for the moment the turbine to be operated solely as a high pressure unit. 20 indicates a ported ring valve that controls the ports, nozzles or passages through which steam passes from a given stage—in this case the extraction stage—to the low pressure portion of the turbine, the latter having one or more pressure stages as desired. This valve may be considered as illustrating any suitable form of valve or regulating device. The valve is oscillated about the turbine shaft by the rod 21 which in turn is moved by the piston of the fluid-actuated motor 22, the structure of which will be described more fully in connection with Fig. 3. Its pilot valve is attached to the lower end of the arm 23 which in turn supports a bell-crank lever 24, one arm of which is connected to the three-arm lever 16 by means of the link 25, rock-shaft 26, arms on the shaft and link 27.

Disregarding for the moment modifications of the action of the admission and stage valves by changes in pressure or in flow, any movement of the governor rock-shaft 18 will simultaneously raise or lower the links 15 and 27 and hence simultaneously open or close the admission valve 8

and the stage valve 20 by equivalent amounts. This means that the stage valve, during high pressure operation, works in response to speed changes with the result of 5 improving the efficiency of the machine by maintaining a substantially constant stage pressure.

Referring to Fig. 3, the piston rod 21 is extended through the cylinder heads, and, 10 on its outer end, is provided with a swivel block that engages and moves between the arms of the fork of lever 30. Levers 23 and 30 are united by the pivot 31. To the lever or member 23 is pivotally connected the 15 stem of pilot valve or regulator 32 which controls the admission of fluid, such as steam or oil, to the motor and the exhaust therefrom in the usual manner. On the lower end of the lever or member 23 is 20 mounted a bell-crank lever or member 24, the long arm of which is connected by the link 25 to the speed governor, while the short arm is connected to the adjustable rod 33 which in turn is attached to the movable 25 head of the diaphragm 34. This is known to the trade as a "sylphon diaphragm" and comprises a corrugated tubular element made of suitable springy metal having a movable head and a stationary 30 base, the latter being supported by a bracket from the turbine. Steam is admitted to the diaphragm chamber by the pipe 35 leading from the stage whose pressure is to be maintained constant—in this case the so-called 35 extraction or first stage 36, Fig. 2, or from the conduit connected to the turbine. Only one stage is provided with a ring valve, but more can be so provided if necessary or desirable. The steam pressure tends to move 40 the head of the sylphon diaphragm to the right, and this action is opposed by the coiled compression spring 37 or equivalent device, said spring being adjustable so that any desired stage pressure can be maintained. Assuming an increase in speed due 45 to a decrease in load on the turbine, the pilot valve is moved, by means of the bell-crank lever 24 (its pivot 38 being fixed for the moment) in a direction to cause the motor 50 to close the ring valve 20 by the proper amount. The movement of the piston moves the lever 30 and with it the pivot 31, and since the pivot 38 remains stationary, or practically so, the pilot valve will be restored 55 to its central position where it closes the entrance and exhaust ports of the motor. Assuming a decrease in speed and a corresponding increase in load the diaphragm moves the pilot valve in a direction to 60 cause the motor to move the ring valve in the opposite direction and admit more steam. On the other hand if a change in stage pressure takes place with or without a change in load, the diaphragm and its co-operating 65 spring will move the bell-crank lever 24

bodily in one direction or the other, as the case may be, and with it the pilot valve, thus enabling the motor to move the stage valve in a direction to compensate for said pressure change. While this action is taking 70 place the link 25 merely swings about its upper pivot without changing the position of the speed governor. The diaphragm operates whenever the stage pressure changes from the predetermined, irrespective of the 75 character of the steam supplied thereto and hence is utilized when the turbine is operating under all conditions. When the turbine operates on the extraction plan it is this sylphon diaphragm which determines the 80 pressure of the steam flowing to the heating, cooking or other devices, and it and its associated parts should be so adjusted or related that the pressure of the steam will be constant or practically so, to attain the best 85 results.

Considering now the low and mixed pressure operation: Steam enters the conduit 11 and flows through the loaded relief valve 39 set to open at any predetermined pressure, 90 such as 16 lbs. absolute for example. This valve may be of any well known or suitable construction. From this valve it flows through a check valve, having a valve 40 carried by a spindle 41 to which is attached 95 an arm carrying a sliding weight 42. For extraction purposes the weight should occupy the position indicated by the dotted lines and for low and mixed pressure, the position shown in full lines. In other 100 words, for mixed pressure service, the valve is inactive, and for extraction service, active, and closing when steam tends to flow toward the turbine. The utility of the valve for extraction purposes is evident from the fact 105 that in some installations the piping leading to the consumption devices has considerable capacity and if said piping were filled with steam when the load was thrown off of the turbo-generator, the amount of steam in 110 said piping would be sufficient to cause the turbine to race. With a valve arranged as described this cannot take place because the instant there is a reversal in the direction of steam flow the valve will automatically 115 close.

It has been heretofore proposed to partially control a mixed pressure turbine by means of a device responsive to pressure changes in the low pressure source. This 120 is satisfactory in cases where the low pressure supply is not subject to sudden and wide variation in pressure, but where such changes do take place they result in momentarily shifting the machine from high 125 to mixed pressure operation and vice-versa, which may give rise to objectionable speed changes and therefore to frequent and unnecessary shifting of the valves. I avoid this objection by providing a measuring de- 130

vice or means which is responsive to changes in the rate of flow of the low-pressure steam and which is unaffected by changes in pressure. To this end, I mount in the low-pressure steam conduit 11 a funnel 43 made in the form of a Venturi tube; *i. e.* a tube in which the bore gradually decreases in cross-sectional area to the throat, and thereafter enlarges at a definite rate to its end in a well-known manner. The effect of this funnel is to temporarily increase the velocity of a selected portion of the steam, that is that passing through the funnel. It is preferable to use a funnel instead of forming a section of the conduit into a Venturi tube because it is much cheaper, and because the funnel can readily be installed in existing stations without changing the piping and because new funnels may readily be substituted for changed operating conditions.

In the throat of the funnel is located a Pitot tube or plug 44 containing a central longitudinal orifice 44^a, Figs. 4 and 5, and connecting orifices 44^b that point down stream. The central orifice 44^a is connected to the pipe 46 leading to a diaphragm 47. 45 indicates a perforated tube having a closed end terminating outside of the funnel and forming the other element of the Pitot tube. This tube 45 may be of the same general nature as the tube shown in Fig. 4 and is arranged with the orifice pointing up-stream. Other forms of measuring devices may be used without departing from my invention. The pressure due to the plug 44 will be equal to the static pressure minus an amount determined by the velocity head due to the action of the funnel while the pressure in the tube 45 will be equal to the static pressure outside of the funnel. In this manner a pressure difference is created that varies with changes in the rate of flow of steam to the turbine, and which is greater than would be the case if either the Venturi tube or Pitot tube were used alone. This pressure difference is communicated by pipes 46 to a diaphragm 47 which may be corrugated if desired to render it more flexible. The diaphragm is located in a chambered casing and to it is attached a stem 48 that is connected by a link to the upper arm of the three-arm lever 16. A spring 49, Fig. 1, is employed to adjust the action of the diaphragm. The movement of the diaphragm has the effect of modifying the relation existing between the speed governor on the supply valve 8 and stage valve 20. This will readily be appreciated from Fig. 2 in which 9 indicates the speed governor and 50 a stationary member through which the governor spindle 51 extends. The weights of the governor as they move in or out bodily move the three-arm lever 16 up or down depending on whether the speed increases or decreases. This movement of the lever is com-

municated to both the supply and stage valves which are illustrated as moving back and forth over the supply ends of the nozzles 52. Now if the lever 16 is tilted one way or the other by the diaphragm 47, either directly or indirectly, it has the effect of closing one valve and opening the other by a corresponding amount. In other words the flow responsive means acts differentially on the valves and the speed governor 75 simultaneously and correspondingly on both valves. The sylphon diaphragm 34 on the other hand acts on the stage valve only as will be readily seen. For high-pressure operation a load may be assumed which 80 requires the valves to occupy the position shown, *i. e.* partially open. Now if the turbine were operating low pressure on the same load the valve 8 should be shut and the valve 20 opened somewhat wider. Inasmuch as the speed governor can only move the valves simultaneously and correspondingly it follows that the governing mechanism would fail under these conditions were it not for the action of the diaphragm 47, 90 said diaphragm establishing such relations between the valves and their ports as will properly proportion the supplies of high and low pressure steam and enable the speed governor to act thereon in the desired manner. To simplify the description I have for the moment disregarded any modification action due to the sylphon diaphragm 34, the action of which is described elsewhere. 95

Assuming that the machine is operating 100 solely on high pressure and the supply of low-pressure steam from some outside source increases until its pressure balances that in the second stage to which the pipe 11 is connected, nothing will happen. If, however, the pressure slightly increases above said value, the valve 39 will momentarily open to atmosphere and a flow will be established which in turn after a brief interval of time causes the diaphragm 47 to act and adjust both the inlet and stage valves to a new relation as determined by the rate of flow. Inasmuch as this part of the apparatus has a lagging time element, the valves will not be readjusted until the flow has existed for an appreciable period of time. This prevents a momentary supply of low-pressure steam—as from one revolution of a rolling mill engine—from shifting the valves to mixed pressure relation only to have them return to their previous positions for high pressure operation as soon as said supply gives out. As soon as the flow is established there is a slight decrease in stage pressure and the valve 39 closes and low pressure steam is fed through the conduit to the second stage. In this governing mechanism it is the aim, in so far as possible, to use low pressure steam and to supplement it with high pressure steam only when necessary because of the addi- 115 120 125 130

tional cost thereof. When operating the turbine on the extraction plan the diaphragm 47 is not utilized and to cut it out of service valves 53 are provided in the pipes 46 leading thereto.

5 Under the usual operating conditions encountered in practice the funnel 43 in the conduit 11 will not be objectionable when the machine is operating on the extraction plan because it offers such a slight resistance to the flow of steam. In those cases where it is objectionable, a valve-controlled by-pass 54 is provided which shunts said funnel when its valve is open. It will be noted that 10 the three-arm lever device or means 16 performs an important part in the governing operation because it ties together and operates the admission and stage valves and because its angular position determines whether the machine will operate on low, high or 15 mixed pressure steam. Inasmuch as said lever is fulcrumed on the speed governor, or what is the same thing in the rock shaft 18, it follows that its angular position can readily be changed without undue work by a 20 diaphragm or other pressure device and this without unduly loading the governor. In so far as its ultimate effect on the valve 20 is concerned, the lever 24 which is connected to the sylphon diaphragm could be mounted 25 directly on the three-arm lever 16 as shown in Fig. 2, but since it is impractical in most cases to do this on account of structural difficulties, I effect the same result by supporting 30 it on the lever 23 and connecting it by links, shaft, etc., to said lever 16.

The stage valve in addition to serving as a means for maintaining the stage pressure constant also serves as a regulating valve to 40 prevent the turbine from running away in case the load is suddenly thrown off and the supply of low pressure steam continues. This action is brought about by the speed 45 governor action on the pilot valve of the motor in a manner to cause it to close said stage valve.

I have shown the measuring device located in advance of the relief valve 39 but in some cases I may locate it between the relief valve 50 and the turbine. As shown, said device is acted upon by the total quantity of low-pressure steam. When located on the other side of the valve it will be acted upon only by the actual amount of steam entering the turbine. The latter arrangement has the advantage of giving strictly isochronous operation. The pressure-responsive device for 55 regulating the second stage valve is not used for speed regulating purposes but serves to correct unavoidable mechanical imperfections in the valve mechanism.

Under some circumstances it is desirable to use the flow measuring device when the turbine is operated on the extraction plan. 60 In such a case the connections from the Ven-

turi tube to the diaphragm 47 coöperating therewith would be reversed, or a Pitot tube may be used without the Venturi tube.

Owing to the use of the ring stage valve in combination with suitable admission 70 valve means, the efficiency of the machine is improved because the working passages throughout the machine are properly proportioned one to the other to convey the steam at its given pressure and volume. As 75 a result of this the pressure in the stage controlled by the stage valve will be constant. This means that a pressure responsive device in the conduit supplying low pressure steam to the controlled stage would 80 be ineffective because the stage valve would immediately open as the pressure increased and close as the pressure decreased. By utilizing a flow responsive device, however, a constant stage pressure can be maintained 85 with its accompanying advantage of increased economy, while at the same time the governing mechanism will be so set as to cause only that amount of high pressure steam to enter the turbine as is necessary to 90 supplement the low pressure supply.

By reason of my improvements the same turbine without change in its structure can be operated in four different ways, as a high pressure machine, as a low pressure machine, 95 as a mixed pressure machine, and as an extraction machine either singly or in connection with other machines delivering energy to the same system and in exact synchronism therewith. This greatly increases the utility 100 of the machine and gives it a very wide application as will readily be appreciated. It is of especial importance for use in driving electric generators in central stations which supply low pressure steam for heating in 105 the winter time and have available considerable low pressure steam at other times.

In accordance with the provisions of the patent statutes, I have described the principle of operation of my invention, together 110 with the apparatus which I now consider to represent the best embodiment thereof; but I desire to have it understood that the apparatus shown is only illustrative and that the invention can be carried out by 115 other means.

What I claim as new and desire to secure by Letters Patent of the United States, is:

1. In combination, a turbine, a valve controlling the admission of high-pressure fluid thereto, a valve controlling the passage of fluid therethrough, a speed governor which controls both of said valves, and a means responsive to changes in the rate of flow of a fluid for modifying the action of the governor on one of said valves. 120

2. In combination, a turbine, a valve controlling the admission of high-pressure fluid thereto, a valve controlling the passage of fluid therethrough, a speed governor which 125

controls both of said valves, and a means responsive to changes in the rate of flow of a fluid which acts differentially on said valves.

5. In combination, a turbine, a valve controlling the admission of high-pressure fluid thereto, a valve controlling the passage of fluid therethrough, a speed governor which controls both of said valves, and a means responsive to changes in the rate of flow of 10 low-pressure fluid for adjusting said valves with respect to their ports and independently of the governor.

4. In combination, a turbine, a valve controlling the admission of high-pressure fluid thereto, a valve controlling the passage of fluid therethrough, a speed governor which controls both of said valves, a pressure-responsive means for adjusting one of the 15 valves independently of the governor, and a means for adjusting both of said valves independently of the governor.

5. In combination, a turbine, a valve controlling the admission of fluid thereto, a 25 ported ring valve within the turbine for controlling the passage of fluid therethrough, a speed governor for controlling the valves, and a means responsive to the pressure existing in a region in the turbine for causing 30 one of the valves to open or close ports within the turbine independently of the governor.

6. In combination, a turbine, a valve controlling the admission of fluid thereto, a 35 gridiron valve controlling the passage of fluid through an intermediate part of the turbine, a motor for actuating it, a regulator therefor, a speed governor that controls the action of the admission valve and the regulator, and a pressure-responsive device which acts on the regulator to cause the motor to move its valve without changing the position of the speed governor.

7. In combination, a turbine, a conduit 45 connected to a region of intermediate pressure of said turbine through which fluid may be either admitted to or extracted from the turbine, a valve controlling the admission of high pressure fluid to the turbine, a ring 50 valve controlling the flow of fluid through the turbine at the point of intermediate pressure, a speed governor which acts on both said valves to simultaneously open or close the same, and a device responsive to the 55 pressure of the fluid flowing in said conduit which acts to regulate the second named valve only.

8. In combination, a turbine, regulating valves therefor, a motor for moving one of 60 the valves, a regulator for the motor, a speed governor that normally controls the valves, a pressure-responsive device, a swinging member, a connection between it and the regulator, and a member connected to the 65 speed governor and to the pressure-re-

sponsive device which is pivotally supported by the swinging member.

9. In combination, a turbine having an inlet, an outlet and a conduit connected to a region of intermediate pressure therein, an 70 admission valve, an intermediate pressure valve in communication with the conduit, a speed governor for controlling the action of the valves, pressure means for modifying the relation existing between the governor 75 and one of the valves, and a means responsive to changes in the rate of flow of a fluid for also modifying the relation existing between the governor and said valve.

10. In combination, a turbine having an 80 inlet, an outlet and a conduit connected to a region of intermediate pressure therein, an admission valve, an intermediate pressure valve in communication with the conduit, a speed governor for controlling the 85 action of the valves, means responsive to pressure changes, means responsive to changes in the rate of flow of a fluid, and a means connecting said pressure and flow responsive means with the speed governor 90 to modify the relation between the valves and the levers.

11. In combination, a turbine having an inlet, an outlet and a conduit connected to a region of intermediate pressure therein, an 95 admission valve, an intermediate pressure valve in communication with the conduit, a speed governor for controlling the action of the valves, means responsive to pressure changes, means responsive to changes in the 100 rate of flow of a fluid, and a device which is connected to both of said means, is tilted by one of them and is moved bodily by the speed governor.

12. In combination, a turbine having an 105 inlet, an outlet and a conduit connected to a region of intermediate pressure therein, an admission valve, an intermediate pressure valve in communication with the conduit, a speed governor for controlling the 110 action of the valves, means responsive to pressure changes, means responsive to changes in the rate of flow of a fluid, a member moved by the governor, connections 115 from said member to the controller of one of the valves, and to one of said means, and a pivotal connection between the governor and member to permit the latter to move independently of the governor.

13. In combination, a turbine having an inlet, an outlet and a conduit connected to a region of intermediate pressure therein, an admission valve, an intermediate pressure valve in communication with the conduit, a speed governor that normally controls the 120 valves, a means responsive to the pressure in said region, a device located in the conduit for creating a pressure difference determined by the rate of flow of fluid therein, a means acted upon by the pressure dif- 125 130

ference which in turn acts differentially on the valves.

14. In combination, a turbine having an inlet, an outlet and a conduit connected to a region of intermediate pressure, a valve controlling the passage of fluid from said region, a governor therefor, a device located in the conduit for creating a pressure difference that bears a definite relation to the quantity of fluid flowing through it, a means subjected to said pressure difference, and a device acted upon by said means to change the established relation between the governor and the valve.
15. In combination, a turbine, a conduit supplying elastic fluid thereto, a valve controlling the passage of said fluid through the turbine, a relief valve in the conduit, a measuring device in the conduit, and means that coöperates with the measuring device and acts on the controlling valve.
16. In combination, a turbine, a conduit supplying low-pressure fluid thereto, a valve controlling the passage of said fluid through the turbine, a valve in the conduit that opens to establish a flow through the conduit and

closes when the flow is established, a measuring device sensitive to variations in the rate of flow of fluid through the conduit, a means acted upon by the device, and a device for causing movements of the means to modify the action of the controlling valve.

17. In combination, a turbine, a conduit supplying fluid pressure thereto, a valve controlling the passage of said fluid through the turbine, a motor for actuating the valve, a controller for the motor, a valve in the conduit that opens to establish a flow through the conduit and closes when the flow is established, a measuring device in the conduit and sensitive to changes in the rate of flow through it, a means acted upon by the device, and a device for causing the means to modify the action of the controller on the motor.

In witness whereof, I have hereunto set my hand this tenth day of February, 1913.

FRED E. NORTON.
